(57) **CLAIM**

The ornamental design for a cabin headliner, as shown and described.

DESCRIPTION

FIG. 1 is a perspective view of a cabin headliner showing our new design;

FIG. 2 is a bottom plan view thereof;

FIG. 3 is a side elevational view thereof;

FIG. 4 is a front elevational view thereof; and,

FIG. 5 is a rear elevational view thereof.

The broken line structure in the drawings is included for the purpose of illustrating environment and forms no part of the claimed design.
